UNITED STATES PATENT OFFICE.

HARRY M. MILLER, OF MILWAUKEE, WISCONSIN.

OUTLET-VALVE.

1,348,233.

Specification of Letters Patent.

Patented Aug. 3, 1920.

Application filed January 17, 1916. Serial No. 72,529.

To all whom it may concern:

Be it known that I, HARRY M. MILLER, a citizen of the United States, residing at Milwaukee, county of Milwaukee, and State of Wisconsin, have invented new and useful Improvements in Outlet-Valves, of which the following is a specification.

My invention relates to improvements in outlet valves for radiator systems.

10 The object of my invention is to provide a valve which can be relied upon to operate under all conditions of ordinary service, which can be easily cleaned or repaired, and in which the incoming water, if admitted 15 to the valve in a rapid stream, will serve to assist the float in acting quickly and facilitate flushing the casing and valve ports.

In the drawings,—

Figure I is a vertical sectional view of a 20 valve casing embodying my invention, drawn to a plane cutting the inlet and outlet ports.

Fig. II is a fragmentary sectional view, drawn to a plane cutting the air relief duct.

25 Fig. III is a horizontal sectional view, drawn to a plane cutting the fulcrum brackets, the inlet duct, however, being shown in full; and Fig. IV is a cross section of the outlet chamber.

30 Like parts are identified by the same reference characters throughout the several views.

A valve casing A is provided with an inlet port B and an outlet port C, the inlet 35 being located in the side near the bottom, and the outlet port being located in the bottom, as is usual in such valve mechanisms. The top of the casing is closed by a cap A' which is preferably screwed in position upon the 40 casing wall. Directly opposite the inlet, the wall of the casing is provided with an extension A'', which is hollow and provides an extension of the casing cavity to receive an auxiliary outlet chamber E and a valve 45 lever F, both of which project into the extension cavity from the central portion of the casing cavity, as shown.

The auxiliary outlet chamber is provided 50 near its inner end with a depending tubular projection, the outer surface of which is tapered, and adapted to fit the outlet port C. The top wall of the chamber is provided with a fulcrum bracket, comprising two upwardly projecting ears, to which the lever F 55 is pivotally connected by a pivot pin f. The short arm of the lever F projects into the

extension cavity and a valve stem G is pivotally connected therewith and supports a valve G' located within the auxiliary chamber E and adapted to close an inlet port g 60 therein. The stem projects through this inlet port, and when the short arm of the lever F is raised, the valve will be held thereby to its seat. The long arm of the lever F is pivotally connected with a float I by 65 which the lever is actuated, the weight of the float normally holding the long arm of the lever depressed, and thus holding the valve to its seat, but when water enters the chamber, the float is thereby lifted and the valve 70 G' is pushed downwardly to open position. The float is located in such a position, that the incoming water pushes against its under surface, or against its lower portion, almost in line with the valve lever F, and the water 75 pressure is thus rendered doubly effective to operate the valve when it enters rapidly enough to acquire momentum. This occurs quite frequently under ordinary conditions, and the valve is therefore very effectively 80 kept from sticking in dirty or greasy water.

The auxiliary chamber is provided with a flange J one side thereof near the bottom. A screw L has threaded engagement with the bottom of the casing and is provided 85 with a large head, one side of which is cut away. The other side of the screw head is adapted to engage over the flange J as shown in Fig III, but when the screw is rotated a one half turn, the flat side of the head will be 90 adjacent to, but will not engage said flange and the auxiliary chamber may then be lifted out and removed, with the float and valve lever, through the top of the casing. When the cap is off, the screw J can easily be 95 reached from above and turned to the desired position.

To provide for an independent delivery 100 of air from the casing, the wall thereof is provided with a duct K which leads downwardly from the upper portion of the casing cavity to the outlet. The wall of this duct is provided with an inlet port K' at its upper end and deliveries through this port are controlled by a valve L which is supported 105 by a stem M. This valve stem carries a screw threaded enlargement M' threaded in a tubular boss N projecting from the side of the casing. The boss N has its outer end closed by a cap O. By removing the cap 110 the valve stem may be rotated to adjust the valve to such a position that it will permit

a very slow escape of air or steam from the interior of the casing and thus prevent air accumulation. The port K' is preferably made large enough to allow a rapid flow of 5 water or steam when fully open, and the valve has its seating face into a broad cone to facilitate flushing operations.

In float operated outlet valve mechanisms, a sudden movement of the float frequently 10 causes it to rap sharply against the wall of the casing, thereby producing a metallic sound audible throughout the room if not through other parts of the dwelling, and this tends to cause annoyance.

15 To overcome this difficulty, my improved valve mechanism is provided with a stop which acts directly upon the lever F near the pivot pin f in a manner to limit the upward movement of the float and prevent it 20 from striking the casing at any point. This stop preferably comprises an arm R which projects above the path of the lever F and is adapted to be struck by the lever when the float moves upwardly. This bracket arm 25 R may be slightly resilient, but in any event, it is located so close to the fulcrum f that the contact of these parts will make no audible sound.

I claim—

30 1. An outlet valve for radiators, including the combination of a casing provided with a side inlet and an outlet in its bottom, and having a lateral extension of the casing cavity located opposite the inlet, an outlet 35 chamber having a tubular outlet projection fitted to the casing outlet, said chamber having an inlet port in its top, a valve within said chamber adapted to close said inlet port against fluid pressure, a lever pivotally supported above said chamber and linked to 40 said valve, and a float having its bottom centrally connected to said lever; said lever having its valve supporting arm in the extension cavity, and its float supporting arm substantially in line with the inlet passage, said 45 lever and the lower portion of the float being in the unobstructed direct path of the fluid entering the casing through said inlet, and subject to fluid momentum pressures 50 and scouring effects of the incoming stream of water.

2. In an outlet valve mechanism for radiators, the combination with a casing having an outlet port in its bottom and an extension 55 in one side near the bottom, said casing having an inlet opposite the extension, a removable auxiliary outlet chamber having a depending tubular outlet projection seated in the casing outlet, and having also a top 60 inlet within the casing extension, an interior valve adapted to close such inlet against fluid pressure, a lever pivotally supported from the auxiliary chamber, a float carried by the end of the lever nearest the casing inlet, and 65 a link loosely connecting the valve with the

lever within and substantially in the direct line of flow of water entering the casing inlet, whereby the lever, link and valve controlled port are subject to fluid momentum pressure and scouring effects from the stream 70 of water entering the casing inlet.

3. In an outlet valve mechanism for radiators, the combination with a casing having an outlet port in its bottom and an extension in one side near the bottom, said casing having an inlet opposite the extension, a removable auxiliary outlet chamber having a depending tubular outlet projection seated in the casing outlet, and having also a top inlet, an interior valve adapted to close such 80 inlet, a lever pivotally supported from the auxiliary chamber, a float on one end of the lever in the path of fluid from the casing inlet, and a link pivotally connecting the other end of the lever with the valve; said 85 auxiliary outlet chamber having a lateral flange and said casing having a rotatable projection adapted in one position to engage said flange, and in another position to release the same. 90

4. In an outlet valve mechanism for radiators, the combination with a casing having an outlet port in its bottom and an extension in one side near the bottom, said casing having an inlet opposite the extension, 95 a removable auxiliary outlet chamber having a depending tubular outlet projection seated in the casing outlet, and having also a top inlet, an interior valve adapted to close such inlet, a lever pivotally supported from the auxiliary chamber and provided with a float in the path of fluid from the casing inlet, and a link pivotally connected with the other end of the lever; said auxiliary outlet chamber having a lateral flange and said 100 casing having a rotatable projection adapted in one position to engage said flange, and in another position to release the same, a cap for the casing adapted when removed to afford access to said rotary projection, and 105 to permit the removal of the float and outlet chamber. 110

5. An outlet valve mechanism for radiator systems, including the combination of a casing having inlet and outlet ports and a float controlled valve, said casing having a duct leading from its upper portion downwardly in the walls thereof to the outlet below the valve, the walls of the duct at its upper end being ported for communication 115 between the interior of the casing and the duct, and the opposing wall of the duct being provided with a lateral threaded extension in line with said port, a nut within said threaded extension, adjustable longitudinally thereof, a valve stem rigidly connected with said nut and provided with a valve controlling the passage of fluid from the interior of the casing into said duct, 120 said valve being provided with an operat- 125 130

ing stem on the opposite side of said nut, and a cap having threaded engagement with said extension and normally covering the operating end of the valve stem.

- 5 6. An outlet valve for radiator systems including the combination of a casing having inlet and outlet ports, and float controlled valve and valve mechanism controlling deliveries of water through said outlet, 10 said casing having a duct leading from its upper portion downwardly in the walls thereof to the outlet below the valve, a regulating valve controlling the inlet to said duct, said casing having a normally capped

aperture affording a means of access to the 15 regulating valve, the valve having a stem in screw threaded engagement with the walls of said aperture, whereby the valve is supported and adjusted by rotation, and the valve comprising a broad cone adapted to 20 facilitate flushing operations.

In testimony whereof I affix my signature in the presence of two witnesses.
